UNITED STATES PATENT OFFICE.

RICHARD WEST ROOTS, OF BALLARAT, VICTORIA, AUSTRALIA, ASSIGNOR OF ONE-THIRD TO STANLEY ROOTS, OF BALLARAT, VICTORIA, AUSTRALIA, AND ONE-THIRD TO JAMES FALCONER, OF WELLINGTON, NEW ZEALAND.

OIL-FILTER.

1,350,521.

Specification of Letters Patent. Patented Aug. 24, 1920.

Application filed February 1, 1919. Serial No. 274,473.

To all whom it may concern:

Be it known that I, RICHARD WEST Roots, a citizen of the Commonwealth of Australia, and residing at 103 Webster street, Ballarat, 5 in the State of Victoria, Commonwealth of Australia, have invented certain new and useful Improvements in Oil-Filters, of which the following is a specification.

This invention has reference to filters for 10 separating impurities from lubricating oils used in internal combustion engines and for other purposes. It is intended for installation in an engine room, garage or other place where dirty oils can be conveniently treated 15 and rendered again fit for use.

Oil used in the crank chambers and particularly when employed as a lubricant in engine cylinders very soon becomes charged 20 with impurities which must be eliminated if the oil is to remain efficient.

According to this invention I utilize a rigid container preferably oval in shape, having two compartments separated by a partition. In one of the compartments is 25 a hollow vertical spindle on which is supported a series of superposed fine gauze traps diminishing in diameters toward the lower end of the spindle.

Heated water is contained in the compartment holding the traps and the dirty oil is 30 fed to the vertical spindle which discharges the same into the lowermost trap. The oil passes upward through the traps and the heated water and overflows through an oil 35 discharge pipe in the partitions into the other compartment, wherein is a fine gauze bucket or screen into which the oil finally passes, and whence the same is discharged. Means are provided for regulating the level 40 of the water in the first compartment and for draining the oil and water from the machine.

But in order that the invention may be 45 thoroughly understood reference is made to the accompanying drawings, in which:—

Figure 1, is a front elevation of the filter, 50 Figs. 2 and 3, details of the series of gauze traps and gauze bucket respectively.

Fig. 4, is a sectional elevation of a trap, 55 Fig. 5, is a plan of Fig. 1, the lids being removed,

Fig. 6, is a longitudinal sectional rear elevation of the container without the traps and bucket, and,

Fig. 7, is a detail of the water regulation means.

The container 8 is divided into two compartments by the partition 9, and another partition 10 forms a corner compartment 10^a which however does not descend to the container floor. In one compartment 11 which is nearly filled with water is a heating coil 12, and the series of traps illustrated in Fig. 2. The water in the compartment 11 rises up within the compartment 10^a.

Referring to Fig. 2 the hollow vertical spindle 13 supports at its upper end a funnel 14 above which is suspended a strainer 15 adapted to receive the oil to be filtered.

The pipe 13 has attached the series of circular traps 17, which are made with depending sides forming curtains 17^a composed of fine wire gauze attached to shallow light solid metal trays 18, which provide the necessary stiffening for the curtains and a solid roof 17^b thereto. In the drawings the series is composed of four traps in diminishing diameters toward the lowest. The diameters are such that each trap is entirely below the area of the trap immediately above. After the oil has flowed down the pipe 13 the same escapes within the lowest trap, and as it is a property of oil to float on water it immediately seeks to escape from the gauze trap to the surface of the water in the compartment. In doing so it passes through the gauze curtain and float upward, but will be caught by the trap immediately above, whence the oil escapes to the next trap and so on until it has risen to the surface of the water. The mesh of the gauze composing the traps should be largest in the lowest trap and decrease to very fine in the upper one. If the oil is not very dirty it will pass through all the gauze curtains freely leaving therein the foreign matter.

Should the lowest or any other of the curtains become choked so that the oil is prevented from passing through the gauze it may escape upward through the pipes 19 from one trap to the next. These pipes have their openings respectively near the lip of the gauze curtains and the floors 17^b of the solid trays as shown. To facilitate freeing the gauze from impurities during the filtering process the spindle or pipe 13 is fitted with a horizontal bar 20 which is hung in the bearings 21. The series of traps can be

moved to and fro in the water to cause the foreign matter adhering to the curtains to be displaced. The sludge is drawn off as required through the cock 22.

After the oil is fed into the funnel 14 and has passed upward through the traps 17 it overflows through an oil discharge comprising a hole 23 into the second compartment 24, wherein is the gauze bucket or screen 25. The use of this screen will only be necessary in the treatment of very dirty oils and such as are not thoroughly cleaned in their passage through the traps. The oil coming into the compartment 24 will pass through the very fine gauze of the bucket 25 and will flow out through the orifices 26. These orifices are made in V shaped lugs 27 which engage in corresponding grooves in plates 28. The faces of the plates and the outer part of the V shaped lugs are scraped and polished to provide oil tight joints. The openings 26 in the bearings coincide with the openings 26^A, in the plates and container. The lower opening 26 will be through the cock 26^B, while the pipe 29 will discharge the oil from the upper openings 26^A. Should the screen 25 become choked the oil may overflow through the slots 30 into the receptacle 31 and thence into the discharge pipe 29.

If choking should occur the screen 25 should immediately be removed and a fresh one substituted while the first is being cleaned. The sludge is drawn from compartment 24 through cock 32.

The water can overflow through an opening 35 into the receptacle 36 but in order to maintain the water at a constant level, which should be a little below the oil discharge pipe 23 in the partition, I provide a discharge pipe 37 which projects into the receptacle 36 and has its end threaded to take the rotatable coupling 38, which has discharge orifices 38^A. By making the discharge orifice lower than the rim of the coupling 38, the upper part of the coupling is always above the surface of the oil and water and can be readily handled. If this coupling is turned the vertical position of the discharge orifices 38^A may be varied so that in consequence the thickness of the film of the oil floating in the compartment 11 may be varied. If water is coming into the filter mixed with the oil the

proper setting of the coupling 38 will maintain the water level constant. It will be observed that there is a body of water in the compartment 10^A. The opening 35 must be in this partition. The various working parts are made so as to be easily removable for cleaning. Thus, the pipe 13 with the traps may be lifted out bodily and plunged into hot water to remove sediment and be then quickly replaced. The same applies to the screen 25 and the strainer 15. Oil flowing into the filter through 13 will pass upward through the gauze traps 17 to the overflow 23 into the compartment 24 and thence through screen 25 and openings 26 to discharge pipe 29 in a condition ready again for use. For ordinarily dirty oils the first compartment treatment will suffice, in which case the discharge pipes can be attached to that compartment to convey the oil from the overflow for use.

What we do claim and desire to secure by Letters Patent of the United States is:—

1. In an oil filter, a container adapted to contain heated water, a series of superposed gauze traps within the container of different diameters and having solid metal roofs, a hollow vertical spindle attached to the traps and discharging into the lowest and smallest trap, short pipes interposed between the gauze traps having their lower ends terminating near the bottom of the traps and their upper ends near the roofs of the traps, substantially as set forth.

2. An oil filter, comprising a container, a partition dividing the container into two main compartments, a second partition forming a corner compartment in one of the main compartments and terminating short of the bottom of the container, straining means in both of the main compartments, the first mentioned partition having an oil discharge opening formed therein near the top thereof and the corner compartment being provided with an overflow opening.

In testimony whereof I have signed my name to this specification in the presence of two witnesses.

RICHARD WEST ROOTS.
